VOLTAGE VARIATOR CONTROL

Harold E. Carson, Indianapolis, Ind.

Application October 12, 1948, Serial No. 54,061

4 Claims. (Cl. 171—119)

1

This invention relates to a voltage variator control for loads, the service of which is variated by volt variation. One broad example of such variable service is a multi-speed fan and the speed thereof is determined by variation in voltage applied to the motor terminals. Such a fan motor, in many instances, is of the shaded pole type, series or universal type or permanent capacitor type although the motor may be of other types. The present voltage variator also has some phase variation included therein. Mention of the motor type of load is not to be considered at restrictive, but merely illustrative of one load, the service of which can be varied by the present invention by primarily varying voltage applied to that load from a relatively constant voltage supply.

The present invention also provides a specific series voltage dropping arrangement. When the invention is applied to fan motors for speed control purposes all the desirable objectives of minimum low speeds with minimum noise is obtained. The present invention is further characterized by the substantially continuous voltage variation throughout the range of the invention.

The chief feature of the invention, therefore, resides in the attainment of the voltage dropping characteristic inherently obtainable from the potential variator herein disclosed.

Other objects and features of the invention will be set forth fully hereinafter.

The full nature of the invention will be understood from the accompanying drawings and the following description and claims.

In the drawings—

Fig. 1 is a perspective view of the one embodiment of the invention looking toward the so-called jumper side thereof.

Fig. 2 is a front view looking at the manual control side thereof.

Fig. 3 is a schematic wiring diagram of the invention.

Fig. 4 is a schematic wiring diagram of a second embodiment of the invention.

In the drawings 10 indicates a plurality of L-shaped laminations. These are assembled together in hollow core form and are retained in that position by bolts and nuts 11. These bolts simultaneously anchor two U-shaped strips 12 and 13 which extend across, as it were, a gap or central hole in the core, but the same are spaced from the ends of the hole and are oppositely disposed relative thereto.

Disposed in this hole is a shaft 14 and mounted on the forward projecting end of this shaft,

which is rotatably mounted by the central portions of these U-shaped strips, is a control knob or handle 15.

The oppositely disposed L-shaped laminations 5 when assembled form two parallel legs of said core. Upon each of these two parallel legs of the core there is mounted a coil 16. This may be of single layer type, but may, as shown herein, be and same preferably is of multiple layer type. 10 For purposes of illustration two layers 16a and 16b are shown and these may be suitably insulated, that is layer from layer as indicated at 16c. The outer layer of wire preferably is of wire suitably japaned or the like for insulation purposes.

The shaft 14 carries inwardly of the strip or stirrup 12, an insulation member 17 and carried thereby is a central conducting member 18a, having fingers 18 that at their free ends terminate in indented portions 18b. These fingers are of spring type and are normally under tension and engage the adjacent face of the outer winding of the respective coils forming thereon the arcuate path 19.

25 The shaft 14 is square in cross section and the hole in the insulation member 17 is also square. Adjacent thereto is a disc 20 and the same has the shoulders 20a on the edge thereof. This disc 20 also has a square hole for shaft mounting. The strip 12 is either apertured or indented as indicated at 22 and a pair of balls 23 are adapted to be seated in said seats 22 and also in the seats 24 formed in the disc 20. The strip 12 includes an inwardly extending tongue portion 25 and this is adapted to selectively engage the shoulders 20a when the shaft 14 is moved to one extreme position of oscillation or the other extreme position. When the ball seats 22 constitute holes there is provided a strap

30 spring 26 having a central opening to accommodate the shaft 15. This spring has reduced ends 27 engaging in offset sockets 28 struck from the strap or stirrup 12. Thus the spring 26 normally constrains the balls into engagement position with the plate 20 and serve to hold the shaft in its rotated position.

The balls, when registering with opposed pairs of seats 24 in said disc yieldingly lock the jumper in one of the two positions, "off" or "high," but permit forcible movement of the jumper 18 to any selected position.

Reference will now be had to Fig. 3. Herein there are indicated two power supply lines 30 and 31. The line 30 may be extended to the load. 35 There is a third line 32 that also is connected to

the load. If desired, lines 30 and 32 may be connected to the supply and lines 30 and 31 connected to the load. The inner layer coil in Fig. 3 is designated by the numeral 33 and is connected at one end as at 34 to the line 31. Its opposite end 35 is connected to one end of the outer coil 36, the other end of which is open. Adjacent thereto is a short coil 37, having one end open and the other end connected by line 38 to the end of coil 33 at 34 as shown.

The other coil structure is similar but reversely disposed and contemplates the inner coil 39, having one end connected at 40 to line 32. Its other end is connected to one end of the outer coil 42. The other end is open. Adjacent thereto is the short coil 43, having one end open and the other end connected by line 44 to the junction 40 and therefore line 32.

The jumper is indicated in this Fig. 3 by the numeral 18 and the contact portions are similarly indicated by the arrow portions 18b. When the jumper is disposed in the dotted line portion indicated by the letter x there is an open circuit arrangement and therefore the load does not receive any energy from the supply. When the jumper is disposed as illustrated by the full line in Fig. 3, it will be noted that substantially all of the inductive resistance is shorted out and the load is substantially across the line and, therefore, is subjected to full voltage. When the jumper is disposed as indicated by the dotted line y substantially all the inductive resistance is included and, therefore, the load is subjected to minimum voltage within the range of the control that can be impressed by this voltage variator.

It will be observed that this variator is of series type and is effective simultaneously upon each inductive resistance to decrease or increase the effect thereof, thus increasing or decreasing voltage dropping effect. When a single layer coil is applied to each leg obviously the coil 33 and the coil 39 will be omitted and then the coil 42 will be directly connected with junction 40 and the coil 36 will be directly connected to junction 34. If three coil layers are employed they may be wound for added inductive or compensating inducting effect and they will be connected in series between junction 34 and line 35 and junction 40 and line 41.

The present invention, therefore, is capable of a wide range modification and is extremely compact and it presents, by virtue of the winding arrangement, the effect of a considerable linear resistance construction.

In Fig. 4 there is illustrated a slightly modified form of the invention. This form is utilized as a vernier device to obtain an output voltage above or below line voltage from a substantially constant voltage source.

Herein lines 50 and 51 may represent the supply lines and 52 and 53 the load lines. Thus as before one line may be direct from line to load. As before inner and outer layers of coils are employed. Inner layer 54 connects to junction 55 at one end and its other end is connected by line 56 to one end of inner coil 57, connected at its other end to junction 58.

This junction connects by line 59 to center tap 60 of outer coil 61. Line 53 connects to center tap 62 of outer coil 63. As before jumper 18 has contacts 18a and 18b. When jumper 18 has its contacts 18a and 18b coincident with center taps 60 and 62 respectively line voltage is impressed upon the load. As the jumper is moved therefrom the voltage impressed upon the load is greater or less than line voltage.

10 While the invention has been illustrated and described in great detail in the drawings and foregoing description, the same is to be considered as illustrative and not restrictive in character.

15 The several modifications described herein as well as others which will readily suggest themselves to persons skilled in this art, all are considered to be within the broad scope of the invention, reference being had to the appended claims.

20 The invention claimed is:

1. A voltage variator comprising a pair of concentric coils, a second pair of concentric coils, line terminals, load terminals and oscillatable finger for each outer coil and arranged for wiping electrical contact with the insulated turns thereof, means electrically connecting the fingers together, means for simultaneously moving both fingers, and core means within each pair of concentric coils, one load and one line terminal having direct connection, and the other line and load terminals having connections to one end of the inner coils, one position of the fingers effecting line voltage application upon the load.

2. A voltage variator as defined by claim 1
35 wherein each outer coil includes an intermediate tap, one having direct connection to a load terminal and the other to a line terminal.

3. A voltage variator as defined by claim 2
wherein the taps are medianly disposed.

4. A voltage variator comprising a core formed of a plurality of internested, L-shaped laminations providing spaced apart leg portions and end portions, a coil layer wound on each leg portion, a bridging member spaced from said core structure, having its opposite ends secured to the opposite end portions, a shaft rotatably supported on said bridging member, an insulating support mounted on and rotatable with said shaft and a pair of wiping contact fingers electrically connected carried by said insulating member and having their ends respectively in wiping contact with the respective coils on the leg portions.
